PAGE 2

FIG. 5

FIG. 6

FIG. 7

FIG. 8

FIG. 9

FIG. 10

FIG. 11

FIG. 12

FIGURE 1 is a perspective view of an electric buffet range embodying my new design;

FIGURE 2 is a front elevational view thereof;

FIGURE 3 is a right-hand end view thereof;

FIGURE 4 is a left-hand end view thereof;

FIGURE 5 is a top plan view thereof;

FIGURE 6 is a bottom plan view thereof;

FIGURE 7 is a perspective view of a modified form of the electric buffet range shown in FIGURE 1;

FIGURE 8 is a front elevational view thereof;

FIGURE 9 is a right-hand end view thereof;

FIGURE 10 is a left-hand end view thereof;

FIGURE 11 is a top plan view thereof; and

FIGURE 12 is a bottom plan view thereof.

The dominant features of my design reside in the portions shown in full lines.

I claim:

The ornamental design for an electric buffet range, substantially as shown and described.
